[57] CLAIM

The ornamental design for a front and side panel unit of
a firebox with automatic feed hopper, as shown and
described.

DESCRIPTION

FIG. 1 is a front view of a front and side panels unit of
a firebox with automatic feed hopper showing my new
design;

FIG. 2 is a side elevational view thereof, the opposite
side being substantially a mirror image of that shown;
and,

FIG. 3 is a side elevational view thereof with the
hopper in open position.

FIG. 1

FIG. 2

FIG. 3
